DESIGN FOR A BEDSTEAD

S. H. Tomlinson, High Point, N. C.

Application July 28, 1933. Serial No. 48,870

Term of patent 3½ years

To all whom it may concern:

Be it known that I, S. H. TOMLINSON, a citizen of the United States, residing at High Point, in the county of Guilford and State of North Carolina, have invented a new, original, and ornamental Design for Bedsteads, of which the following is a specification, reference being had to the accompanying drawing, forming part thereof, in which drawing—

Fig. 1 is a perspective view of a bedstead showing my new design.

Fig. 2 is an end view looking in the direction toward foot and head.

I claim:

The ornamental design for a bedstead, as shown.

S. H. TOMLINSON.
